Patented June 20, 1916.

UNITED STATES PATENT OFFICE.

HARRISON W. HICKS, OF HUNTINGTON, INDIANA.

HAT-PROTECTOR.

1,187,622.

Specification of Letters Patent. Patented June 20, 1916.

Application filed March 3, 1915. Serial No. 11,913.

To all whom it may concern:

Be it known that I, HARRISON W. HICKS, a citizen of the United States, residing at Huntington, in the county of Huntington and State of Indiana, have invented certain new and useful Improvements in Hat-Protectors, of which the following is a specification.

My invention relates to hat protectors.

10 The primary object of my invention resides in the provision of an improved means detachably associated with the inner band of a hat for preventing persons from taking the wrong hat, the improved means consisting essentially of a guarding bar or prong which extends laterally from the inner side of the hat, thereby preventing the hat from being disposed about the head of the taker.

20 Another object of my invention resides in the provision of a novel means associated with the guarding means for holding the same in an operative position, the said holding means having associated therewith, for 25 coöperation with the guard, a novel means for preventing the operation of the holding means, for preventing the guarding means from being accidentally placed in an operative position so as to cause no inconvenience 30 to the wearer and user of the device.

A further object of my invention resides in the provision of a novel resilient means associated with the holding means that will automatically cause the holding means to 35 engage the guarding means.

A still further object of my invention resides in the provision of a novel means for removably securing the entire device to the hat band.

40 A still further object of my invention resides in the provision of a novel means associated with the attaching means or supporting plate of the device for facilitating the supporting or hanging of the hat to 45 which the device is attached, to any convenient place.

A still further object of my invention resides in the provision of a device of the character described that is simple in construction, efficient in operation and one that 50 can be manufactured and placed on the market at a minimum cost.

Other objects as well as the nature, characteristic features and scope of my invention will be more readily understood from 55 the following description taken in connec-

tion with the accompanying drawings and pointed out in the claims forming a part of this specification.

In the drawings: Figure 1 is a side elevational view of my invention applied to the inner band of a hat, the latter being shown in longitudinal section; Fig. 2 is a transverse sectional view of my invention applied to the inner band of the hat, only a portion of the hat being shown in transverse section; Fig. 3 is a perspective view of my invention showing the guarding bar or prong in an operative locked position; Fig. 4 is an enlarged fragmentary vertical sectional view taken through the plate showing the guarding bar and holding means in an operative or locked position; and Fig. 5 is an enlarged fragmentary front elevational view, illustrating to advantage the manner in which the sliding supporting means is positioned for preventing the holding means from engaging the guarding means.

Referring more particularly to the drawings in which similar reference numerals designate like or corresponding parts throughout the different views, I provide a hat 1 with an inner band 2, to which is removably secured my improved hat protector, generally designated 3. The hat protector in this instance consists essentially of a preferably rectangular shaped plate 4 formed of metal or other desired material, the plate being curved longitudinally as at 5 so as to be readily insertible between the band and the inner surface of the hat and in order that no inconvenience will be caused the wearer. Formed integral with and extending from one of the longitudinal edges of the plate are parallelly arranged strips, the latter being bent adjacent their points of juncture with the plate and arranged in spaced parallel relation with the plate to provide spring clamping arms 6. Tongues 7 formed preferably by striking out the metal, are provided on the inner surfaces of the strips which, when the strips and the plates are arranged in straddled relation about the inner band 2, are adapted to engage the inner band of the hat and thereby prevent accidental or other movement of the device. Also extending from the longitudinal edge, at a point intermediate the clamping arms 7 and preferably formed integral with the plate, is a projection 8, the sides of which converge toward the outer end. Hinge ears 9 are formed integral with

the front face of the plate at a point slightly above the plane of the upper longitudinal edge, between which ears is pivotally mounted, preferably by means of a pin 10, another 5 ear 11 which carries a lug 12 and to the outer surface of which lug is rigidly secured a guarding bar or prong 13, the inner edge of which is arranged in alinement with the inner edge of the lug and which inner ends 10 are adapted for abutting relation with the front face of the projection when the bar is in its lowermost position or laterally arranged with respect to the projection.

In order to removably hold the bar 13 in 15 a substantially rigid and laterally extending position on the projection, I have pivotally mounted a catch 14 on the projection at a point above the pivotal mounting of the bar 13, by means of a suitable fastening 20 element 15. The catch in this instance is formed preferably from a single strip of metal, bent intermediate its ends and having the respective end portions arranged in planes substantially parallel with each other. 25 One side of the plate is reduced to provide a recess 16, the inner end of which, when the catch is in an operative position, prevents upward movement of the bar 13. The side edge of the catch in which the recess 16 is provided, is tapered as at 17, gradually 30 from a point above the point of distortion to the recess in order to facilitate the operation of the device in a manner to be hereinafter described.

25 For the purpose of causing the catch 14 to automatically engage the bar 13, I have rigidly mounted a leaf spring 18 on the projection above the catch by means of a suitable fastening device 19, the spring being 40 slightly curved and having its free end arranged at all times in intimate contact with one edge of the catch as illustrated to advantage at 20.

In order to prevent the accidental locking 45 of the guard bar 13 when it is not desired to make use of this protecting means, I have provided a supporting strip 21 and slidably mounted the same between the ears 9 and the upper longitudinal edge of the plate 50 4, the free ends of the strip being bent upon themselves and engaged upon the rear surface of the projection in order to prevent the accidental displacement of the strip from its position. The upper edge of the 55 strip is provided at a point substantially intermediate its ends with an arcuate recess 22, which, when arranged beneath the pivot point of the guard bar, allows the inner ends of the bar 13 and the lug 12 to be arranged in abutting relation with the plate, consequently allowing the catch 14 to be 60 operatively engaged about the bar, but when the plate is slid longitudinally of the device, the upper edge of the supporting strip being then arranged directly beneath

the inner ends of the lug and the bar, prevents the ends from being arranged in their lowermost or abutting position and also prevents the inner end of the recess 16 from being engaged about the upper surface and 70 the bar 13. Although the pin can extend laterally from the plate there is no restraining means therefor and should a wearer or user of this device place the hat on his head when the supporting strip is arranged 75 to prevent the locking of the bar, the latter will, when engaged by the head of the wearer, be shoved upwardly into a vertical or inoperative position, the upward movement being facilitated by the tapered portion 17 of the catch 14. A finger piece 23 is rigidly carried by the strip and preferably held thereon by means of a fastening device 24, the said finger piece facilitating the sliding of the strip 21.

When it is desired to hang the hat when there is no ordinary supporting means, I have attached a cord 25 to the upper edge of the projection, the outer end of the cord engaging the attaching member 26, which 90 includes essentially a strip provided with openings adjacent the respective ends thereof, one of which openings receives the cord 25 and the other has a suitable thumb tack or like device extending therethrough, the 95 pointed end of which is adapted for engagement with the wall of a building or other convenient place.

The operation of my invention is as follows: Assuming that the device has been applied to the inner band of a hat, in the manner described and that the wearer of the hat desires to hang the same on an ordinary hook, at the same time making use of the hat protector, preparatory to hanging the 105 hat, the supporting strip 21 is slid, by means of the finger piece 23, until the recess 22 is positioned beneath the pivotal supporting means of the bar 13, whereupon the said bar is allowed to move downwardly into 110 position extending laterally from the projection so as to be rigidly engageable by the automatically operated catch 14. Now, it will be readily apparent that when a person secures the hat and places it on his head, 115 the bar 13 will prevent the hat from being positioned comfortably on the head and at the same time inform the person that he has obtained the wrong hat. The wearer of the device will ordinarily have the recess in 120 the locking strip 21, arranged to one side of the pivotal supporting means of the bar so that the retaining means will not engage the bar, even though the latter be in a laterally extended position and should it be 125 in this position when the hat is applied to the head of the wearer, the bar will move upwardly into an inoperative position and will not inconvenience the wearer to any extent.

Although I have shown and described the preferred embodiment of my invention, I desire it to be understood that I am not to be limited to the exact details shown. However, 5 great stress should be laid upon the arrangement of the novel holding means removably associated with the guarding bar as well as the supporting strip coöperating with both of these parts for controlling the operation 10 of the arrangement.

From the above description taken in connection with the accompanying drawings, it can easily be seen that I have provided a device that is simple in construction, containing but a few simple parts that can be cheaply manufactured and assembled and when assembled can be placed upon the market and sold at a minimum cost.

It will be understood that the above description and accompanying drawings comprehend only the general embodiment of my invention and that various minor changes in detail of construction, proportion and arrangement of the parts may be made within 25 the scope of the appended claims and without sacrificing any of the advantages of my invention.

Having thus fully described my invention, what I claim as new and desire to secure 30 by Letters Patent, is:—

1. In a hat protector, the combination with an attaching plate, a bar pivotally mounted thereon and adapted to be swung vertically and downwardly into a laterally 35 extending position therefrom, a resiliently controlled catch pivotally mounted on the plate and provided with a recess for automatic engagement with the bar for preventing upward movement of the bar, and 40 a supporting strip slidably mounted on the plate and provided with a recess for coöp-

erating with the bar for either holding the bar in a vertical or horizontal position.

2. In a hat protector, in combination with an attaching plate, a pivotally mounted 45 guarding bar on said plate, a supporting strip slidably mounted on the plate beneath the pivotal connection with the bar, said plate normally preventing the bar from assuming an operative position and being 50 further provided with a recess to allow the bar to assume an operative position, means for facilitating the sliding of the strip and a pivotally mounted and resiliently controlled catch for automatically engaging 55 and removably holding the bar in a laterally extended position from the plate.

3. In a hat protector the combination with an attaching plate, a projection extending from the upper edge of the plate, a guard 60 bar pivotally connected to the extension, a strip engaged about the projection and slideable longitudinally on the upper edge of the plate, said strip being normally positioned beneath the bar for supporting the 65 bar in a vertical position and provided with a recess to allow the bar to assume a laterally extending position, a spring catch pivotally mounted on the projection above the pivot point of the guard bar and provided with a 70 recess for automatically engaging and removably holding the guard bar in a laterally extending position, and a spring pivotally mounted on the projection for acting upon the catch. 75

In testimony whereof I affix my signature in presence of two witnesses.

HARRISON W. HICKS.
